US00D611514S

(12) **United States Design Patent**
Fukano et al.

(10) **Patent No.:** US D611,514 S
(45) **Date of Patent:** ** Mar. 9, 2010

(54) **ELECTRIC ACTUATOR**

(75) Inventors: **Yoshihiro Fukano**, Tsukubamirai (JP);
Shoichi Makado, Tsukubamirai (JP);
Junichi Saitoh, Tsukubamirai (JP)

(73) Assignee: **SMC Corporation**, Chiyoda-ku, Tokyo (JP)

(**) Term: **14 Years**

(21) Appl. No.: **29/338,924**

(22) Filed: **Jun. 19, 2009**

(30) **Foreign Application Priority Data**

Jan. 7, 2009 (JP) 2009-000184

(51) **LOC (9) Cl.** **15-09**

(52) **U.S. Cl.** **D15/143**
